MULTIPOINTED ELECTRODE

Robert Gorden Hanneman, Cleveland, Ohio, assignor to Air-Maze Corporation, Cleveland, Ohio, a corporation of Delaware

Application January 23, 1947, Serial No. 723,704

3 Claims. (Cl. 250—27.5)

1

This invention relates to improvements in electrodes and more particularly to discharge electrodes normally employing voltages of the order of a few thousand volts up to ten thousand volts or higher.

An object of the present invention is to provide an electrode of the type described having a high emission efficiency.

Another object of the present invention is to provide an electrode of novel construction providing an enormous number of separate emission points arranged in a novel manner so that they may be evenly spaced and oriented 360 degrees about a central axis.

Another object of the present invention is to provide an electrode adapted to be constructed of cheap material easily obtainable and yet having a large emitting surface, great inherent strength and adapted for long use without failure.

Other objects and advantages of the present invention will appear from the accompanying specification and drawings and the essential features thereof will be set forth in the appended claims.

In the drawings,

Fig. 1 is a fragmental front elevational view of a particle-collecting panel using my improved electrode;

Fig. 2 is a transverse sectional view taken along the line 2—2 of Fig. 1;

Fig. 3 is a greatly enlarged side elevational view of one of the electrodes of Fig. 1 and taken approximately along the line 3—3 thereof;

Fig. 4 is a greatly enlarged view of the untwisted material from which the twisted electrode of Fig. 3 is formed;

Fig. 5 is an enlarged sectional view taken along the line 5—5 of Fig. 1; while

Fig. 6 is a view showing another embodiment of my invention.

In the form of my invention shown in Figs. 1, 2 and 5, I have chosen to illustrate a particle collecting panel like that shown and described in my copending application, Serial No. 660,312, filed April 8, 1946, to which reference may be had for further description if necessary. The panel shown in Fig. 1 is similar to that disclosed in Fig. 11 of the above-mentioned copending application. It comprises a frame 10 in which is mounted a zig-zag collecting electrode 11 of sheet form and preferably of woven screen either bare or covered with flocking material. If desired, other collecting electrodes 11a may be provided in the form of flat sheets of screen material extending across the front and back of the panel as shown

2

in Figs. 1 and 2. A series of discharge electrodes 12 constructed according to my present invention are supplied intermediate the zig-zag folds as clearly shown in Fig. 2. Each of these electrodes 12 is constructed of a twisted length of screen wire as shown in Fig. 3, and which will be later described more in detail. At its lower end, each of the electrodes 12 is secured to the hooklike end 13a of a holder 13 which in turn is mounted 10 in an insulator 14. Plates 15 secured to the frame 10 hold the insulators in position. A wire 16 welded to the holder 13 supplies the electrical charge to the electrode 12. At the upper end each electrode is secured to the hooklike end 17a 15 of a holder 17 which is mounted in an insulator 18 held in position by plates 19 secured to the frame 10. A spring 20 in a cuplike recess of the insulator 18 presses against the head 17b of the holder 17 so as to place the electrode 12 under 20 tension. In practice, the electrodes 12 are given an electrostatic charge of one sign while the collecting electrodes 11 are given a charge of the opposite sign. For instance, in one form of my invention, I provide a power pack, not shown, and connect the negative side thereof to the wire 16 which supplies a charge to all of the electrodes 12. The other side of the power pack is connected through ground to the electrodes 11.

Referring now to Figs. 3 and 4, my present 30 invention contemplates the construction of the electrodes 12 from a long narrow strip of fine mesh wire screen twisted about its central axis. Fig. 1 is slightly enlarged as to the electrodes 12, while Figs. 3 and 4 are very greatly enlarged as 35 will presently appear. In one form of my invention, the strip of Fig. 4 is formed from a standard copper screen woven 120 meshes to the inch from wire having a diameter of .0035 inch and the openings in the mesh measure .0046 inch across. 40 In preparing the electrode, I prefer to remove the two outermost strands of longitudinally extending wire, the original position of which is indicated in Fig. 4 by the dot-dash lines 21. In this embodiment, I have left five longitudinal wires 45 22, although the number of such wires may be varied as desired, as will readily be understood by those skilled in this art. The untwisted strip, as illustrated in Fig. 4, would consist of five longitudinally extending wires and an extremely large 50 number of short filaments 23 extending crosswise thereof, there being approximately 120 of such wires per inch of electrode when formed as just described. The free ends 23a extending laterally beyond the outermost longitudinally extending 55 wire would each be of a length equal to 0.10 to

.013 inch in the embodiment illustrated. Each of these ends 23a is a wire .0035 inch in diameter, as previously mentioned, and the myriad of sharp points thus exposed on each electrode 12 gives a very high emission efficiency.

The strip of Fig. 4 is preferably twisted about its central longitudinal axis which I have shown in Fig. 3 as clearly as possible in this type of drawing. It results from this construction that the points 23a are thus arranged in two helices, each regularly arranged about the central longitudinal axis of the electrode 12. It results from this construction also that the points 23a are arranged progressively in a series each of which is oriented at a slightly different angle relative to the electrode axis as compared to the adjacent point 23a above or below it. The distance between adjacent points 23a thus becomes somewhat greater than the spacing shown in the untwisted strip of Fig. 4.

It will be noted with reference to Figs. 1 and 2 that the arrangement of the points 23a in two helices as described in connection with Fig. 3, provides a series of emission points 23a oriented about 360 degrees and tend to send electrostatic charges in every direction toward the collecting electrodes 11 and 11a. Thus, any particles passing through the panel in the direction of the arrows of Fig. 2 will have to pass through the electrode 11.

It results also from the above construction that the discharge from the electrode 12 is very even along the entire length thereof and is not concentrated at various points as is so common in electrodes of this type. The woven wire structure of Figs. 3 and 4 will be recognized as a very strong physical construction adapted to withstand tension and abuse without breaking. There is some inherent flexibility in the twisted electrode of Fig. 3 and I provide additional resiliency by the use of the spring 20 as illustrated in Fig. 5.

Another use of my invention is illustrated somewhat diagrammatically in Fig. 6. Here I have shown a rectifying tube 24 to which alternating current is fed so as to produce a pulsating direct current in a well known manner. The

anode 25 is preferably a cylinder completely surrounding the central cathode 26 which is of my improved form, as shown and described in Fig. 3. The cathode is supported by wires 27 and 28 in the usual manner so as to hold the cathode 26 under tension. Here again, the arrangement of a myriad of emission points 23a in two helices provides a very efficient emission from the cathode in all directions toward the anode. The open character of the screen mesh electrode provides additional emissivity, particularly in the case of gas filled tubes.

What I claim is:

1. An electrode comprising a strip of woven screen having filaments crossing at right angles, there being long filaments running lengthwise of said strip and a series of short filaments running crosswise thereof, said short filaments extending laterally beyond said long filaments providing a series of sharp points along the side of said strip, and said strip being twisted about a central axis generally parallel to said long filaments.

2. An electrode comprising a strip of woven screen having metal filaments crossing at right angles, there being a plurality of parallel long filaments running lengthwise of said strip and a series of parallel short filaments evenly spaced and running crosswise of said strip, said short filaments extending laterally beyond said long filaments on each side of said strip providing two series of sharp points, and said strip being twisted about a central axis generally parallel to said long filaments.

3. An electrode comprising a strip of woven screen having metal filaments crossing at right angles, there being a plurality of parallel long filaments running lengthwise of said strip and a series of parallel short filaments evenly spaced and running crosswise of said strip, each of said short filaments extending the same distance laterally beyond said long filaments on each side of said strip providing two series of sharp points, and said strip being twisted about a central axis generally parallel to said long filaments, providing two series of sharp points each arranged substantially in a helix about said central axis.

ROBERT GORDEN HANNEMAN.

Certificate of Correction

Patent No. 2,440,370.

April 27, 1948.

ROBERT GORDEN HANNEMAN

It is hereby certified that error appears in the printed specification of the above numbered patent requiring correction as follows: Column 2, line 55, for "0.10" read *.010*; and that the said Letters Patent should be read with this correction therein that the same may conform to the record of the case in the Patent Office.

Signed and sealed this 29th day of June, A. D. 1948.

[SEAL]

THOMAS F. MURPHY,
Assistant Commissioner of Patents.
